Primary Examiner—Alan P. Douglas

[73] Assignee: **Teracom Components AB**, Horby, Sweden

Assistant Examiner—Lavone D. Tabor

Attorney, Agent, or Firm—McCormick, Paulding & Huber

[**] Term: 14 Years

[57] **CLAIM**

[21] Appl. No.: 46,806

The ornamental design for a grounding component for electric cables, as shown and described.

[22] Filed: Nov. 13, 1995

DESCRIPTION

[30] Foreign Application Priority Data

May 19, 1995 [SE] Sweden 95-1029

FIG. 1 is a bottom perspective view of the grounding component;

[51] LOC (6) Cl. 13-03

FIG. 2 is a top perspective view of the grounding component;

[52] U.S. Cl. D13/133

FIG. 3 is a first elevational view of the grounding component;

[58] Field of Search D13/133, 148,
D13/149, 150; 174/78; 439/92, 95, 98,
100, 101, 108

FIG. 4 is a second elevational view of the grounding component;

[56] References Cited

FIG. 5 is a third elevational view of the grounding component;

U.S. PATENT DOCUMENTS

FIG. 6 is a fourth elevational view of the grounding component;

D. 243,407 2/1977 Mooney et al. D13/149
D. 339,792 9/1993 Nardi et al. D13/149
3,274,447 9/1966 Nelson 317/61
3,515,948 6/1970 Gutshall 317/61

FIG. 7 is a top plan view of the grounding component; and,

FIG. 8 is a bottom plan view of the grounding component.
